W. HOWARTH

ENDLESS BELT

Filed Dec. 22, 1922

INVENTOR:

By William Howarth
Wm Wallace White
ATTY.

UNITED STATES PATENT OFFICE.

WILLIAM HOWARTH, OF ROCHDALE, ENGLAND.

ENDLESS BELT.

Application filed December 22, 1922. Serial No. 608,516.

To all whom it may concern:

Be it known that I, WILLIAM HOWARTH, a subject of the King of Great Britain, residing at Marland, Rochdale, in the county 5 of Lancaster, England, have invented new and useful Improvements in Endless Belts, of which the following is a specification.

The invention relates to the manufacture of endless and jointless belts or bands from 10 pliable or flexible material such as leather in an economical manner whereby waste of material is reduced to a minimum. To effect this object, according to the invention a piece of leather or other desired material is 15 marked out in closely set coils the coils being double the width of the belt required, commencing with a loop at one corner of the material and terminating with a loop at or near the centre. The width of the strands of the 20 loop is the width of the belt and the double width of the rest when cut from the piece is divided along the centre from loop to loop to correspond with the width of the loop strands and when so cut will open out to 25 form an endless and jointless band.

The accompanying drawing illustrates the invention clearly.

A piece of leather or other material is used and is indicated at *a*. This piece *a* will be 30 marked out as shown. The full lines represent the spiral coils designed to fill as much as possible the area of the material *a* and these full lines of the coil are double the width of the intended belt or band. The 35 ends of the coil terminate in loops, the proper width of the belt, and when the coil is cut out, as marked, from the piece *a*, there is left as waste the shaded part only. The cutting is then continued from the loops along the 40 dotted line to divide the material forming the coils which can then be opened out into

an endless and jointless band. Such a jointless band when cut from a piece of thin flexible leather or other material is particularly suitable for use with small diameter pulleys, 45 for which purpose a joint or fastening in a belt is an objection, and a source of weakness.

The method is also applicable for cutting round leather belting, from leather of the 50 requisite thickness. The belt in this case, after cutting, is rounded in the usual way.

The lengths of belt which may be made in accordance with my invention are limited only by the size or area of the piece of mate- 55 rial.

What I claim as my invention and desire to secure by Letters Patent is:—

1. The method of forming an endless belt, which consists in cutting the material from 60 which the belt is to be made to form a compact coil, said coil being twice the desired width of the belt and merging at its opposite ends into loops, the width of the material of the loops being that of the desired 65 width of the belt, and cutting along the center line of the coil from loop to loop.

2. The method of forming an endless belt, which consists in marking a series of lines upon the material from which the belt is to 70 be cut to form a compact coil, said coil being twice the desired width of the belt and merging at its opposite ends into loops, the width of the material of the loops being that of the desired width of the belt, cutting along 75 the lines forming the coil, a line drawn along the center of the coil from loop to loop, and cutting along said line.

In testimony whereof I have signed my name to this specification.

WILLIAM HOWARTH.
